United States Patent Office

Des. 191,837
Patented Nov. 28, 1961

191,837

TABLE CASTER

James B. Swett, 8 Devonshire Drive, Barrington, R.I.

Filed Aug. 15, 1961, Ser. No. 66,355

Term of patent 14 years

(Cl. D44—7)

FIG. 1.

FIG. 2.

FIG. 3.

FIG. 1 is a top plan view of a table caster, showing my new design;

FIG. 2 is a front view in elevation of the same; and FIG. 3 is a side view in elevation of the same.

I claim:

The ornamental design for a table caster, as shown.
